CARL TRINKLE, OF CINCINNATI, OHIO, ASSIGNOR TO THE BALDWIN COMPANY, OF CINCINNATI, OHIO

GRAND PIANO ACTION

Application filed November 24, 1930. Serial No. 497,795.

Many improvements have been attempted to obtain an easy touch of the key and a fast acceleration of the piano hammer in grand piano actions, but these improvements have 5 been attempted at certain points that did not give the desired result to the artist. In the present invention a cam acts directly on the hammer shank, giving an easy touch and acceleration of the movement of the hammer 10 that enables the average performer to produce fortissimo effects that are usually possible only to the artist of great strength.

In the drawings Fig. 1 is a side view of the action and key when at rest and Fig. 2 15 is a view from the same angle when the key is down and the jack has moved forward into the depression of the underside of the cam and the hammer is engaged by the back-check.

20 A grand piano action has a key 1 with a capstan 2 that supports a wippen 3. Pivoted on the wippen 3 is a cam lever 4 that is operated by a jack 5 that is pivoted at the forward end of the wippen 3. A spring 6 25 is fastened in the cam lever 4 and bears down on a projection at the rear of the jack 5 imparting a lifting effect on the cam lever 4 and causing the stop button 7 to bear against the stop 8 on the wippen 3.

30 The hammer 9 is attached to the hammer shank 10 which is pivoted to a flange 11 that is screwed to a rail 12. A back-check 13 is attached at the rear of the key 1 at a position to engage the heel of the hammer 9 in the usual manner. A let-off button 14 is 35 screwed to the under face of the rail 12 in such a position as to engage the forward end of the jack 5 at the last part of the stroke.

When the key 1 is depressed the capstan 40 2 raises the wippen lever 3. At this time the jack 5 is resting under the knuckle portion of the cam lever 4 causing it to roll evenly under the hammer shank 10 thereby raising the hammer 9 with acceleration toward the 45 string 15, as the contact point of the cam lever 4 approaches the pivot pin where the hammer shank is attached to the flange 11.

At the last $\frac{1}{8}$ " more or less, of the key stroke, the forward end of the jack 5 comes 50 in contact with the let-off button 14 causing

the top of the jack to move out from under the knuckle portion of the cam lever 4 just before the hammer 9 strikes the string 15. As the jack moves free from the knuckle portion of the cam lever 4 the cam lever drops down with its padded recessed portion resting on the head of the jack 5 letting the hammer 9 drop back until its heel engages the back-check 13.

In normal operation the hammer 9 moves 60 with sufficient inertia to cause it to continue to rise after the jack is tripped and to strike the string 15 before dropping back on the back-check 13. When the key 1 starts to rise as for repetition, the jack 5 is pulled back under the knuckle portion of the cam lever 4 by the spring 6 while the weight of the hammer 9 is carried by the back-check 13.

It is possible to build a cam shaped piece on the bottom of the hammer shank 10 and 70 also possible to make part of the cam action on the hammer shank 10 and part on the cam lever 4 and obtain the same results. This cam lever 4 can also be controlled by a broken or jointed jack which would be pivoted both 75 on the wippen 3 and the cam lever 4 but for simplicity the present jack 5 is preferable.

What I claim as my invention is:

1. In a grand piano action, a hammer head 80 swung on a straight hammer shank, a cam lever, controlled by a jack, operating the straight hammer shank and means for causing the jack to escape under the cam lever, and the hammer head to return part way to starting position.

2. In a grand piano action, a hammer head 85 swung on a straight hammer shank, a cam lever adapted to operate the hammer shank and means for the cam lever and straight hammer shank to partially return to starting 90 position.

3. In a grand piano action, a hammer head 95 swung on a straight hammer shank, a cam lever controlled by a jack, operating the straight hammer shank and means for causing the jack to escape under the cam lever.

CARL TRINKLE.
